UNITED STATES PATENT OFFICE

HAROLD A. WHEELER, OF GREAT NECK, NEW YORK, ASSIGNOR TO HAZELTINE CORPORATION

RADIO RECEIVING APPARATUS

Application filed July 7, 1931. Serial No. 549,149.

The present invention relates to the selection of a radio-frequency signal being transmitted on one carrier frequency and the simultaneous reduction of interference being transmitted on other frequencies not greatly different from the frequency of the desired signal.

The invention is particularly applicable to a superheterodyne type of receiver. It is well known that the superheterodyne is sensitive to signals of two frequencies when set to receive any given frequency. The two frequencies differ from each other by twice the amount of the off-set or intermediate frequency to which the intermediate-frequency amplifier is permanently tuned.

It is a common practice to employ a signal selecting system to amplify the desired frequency of the two carrier frequencies to which the superheterodyne receiver responds, the desired frequency herein being called the signal frequency, and which signal selecting system attenuates the undesired carrier frequency or disturbance occurring at the other frequency, herein called the "image" frequency.

The relative attenuation of the "image" frequency can be increased by simultaneously tuning several selective circuits to the signal frequency. However, if the station transmitting at the "image" frequency comes in rather strong, it is difficult to differentiate between the signal and "image" frequencies.

It is the object of the present invention to overcome this disadvantage in a superheterodyne receiver.

To accomplish this object it is proposed to attenuate the undesired "image" frequency by the use of a special rejector circuit comprising an input transformer of which the secondary

is tapped to constitute the connection to the input of the radio-frequency amplifier or of the first detector in a manner similar to that disclosed in U. S. Patent No. 1,680,424, issued August 14, 1928, to William A. MacDonald. The tap is so selected that the terminals of the portion of the secondary coil are at node potential relative to currents of the "image" frequency. However, such a system results in the by-passing of a portion of the signal

current with a consequent loss of the signal energy.

It is therefore another object of the present invention to provide an improved radio receiving apparatus in which the attenuation of the "image" frequency obtainable by means of the tapped coil just described may be had, and yet one in which there will be no ultimate loss in amplification or gain incident to the rejector action.

These and further objects will be apparent in connection with the following description when considered in connection with the drawing.

In accomplishing the objects of the invention, a signal selecting system is provided comprising an input transformer having a tuned secondary, the tuning of which may be varied to cause the tuned circuit to respond to frequencies covering the broadcast band, for instance. The secondary of said transformer is tapped at such a point that the unused portion of the transformer together with the tuning condenser will constitute a by-pass to currents of the "image" frequency. In other words, the terminals of the tapped inductance will be at node potential relative to the signal frequency. The tapped portion of the input inductance is connected with a second tuned circuit comprising an inductance and capacitance, by means of a link circuit which includes a portion of the capacitive reactance of the second tuned circuit. A capacity may also be included in the link circuit for the purpose of causing it to respond to a current of a definite frequency, as may be desired. The inductance of the second tuned circuit may be tapped in a similar manner to provide for further "image" frequency reduction.

Having thus briefly described the invention, attention is invited to the accompanying drawing which shows a selective circuit embodying the present invention.

The antenna or input circuit comprises antenna 1, ground terminal 2, and the primary coil 3. The first tuned circuit comprises secondary coil 4 and variable tuning condenser 5, the secondary coil 4 being coupled to the primary coil 3. The second tuned cir-

cuit comprises coil 9, variable tuning condenser 11, and series condenser 8. The second tuned circuit is coupled to the first by means of the common ground connection and 5 the coupling condenser 7 connected between the intermediate tap 6 on coil 4 and the series condenser 8. The intermediate tap 10 of coil 9 may be in turn connected to the grid or input terminal of a superheterodyne system 10 of which only the vacuum tube 12, which may be the first detector or radio frequency amplifier, is indicated. Tuning condensers 5 and 11 may have similar electrical characteristics and be arranged for uni-control, as 15 indicated in the drawing, as by mounting on the same shaft.

The antenna coil 3 is coupled mostly to the lower part of the coil 4, according to any satisfactory arrangement, many 20 of which are commonly used. The two tuned circuits are simultaneously tuned by means of the tuning condensers to the signal frequency, which may be, for instance, any frequency within the broadcast band, 25 that is, 550 to 1500 kilocycles. The superheterodyne system is usually designed so that the "image" frequency lies above the signal frequency and may fall within the range of 30 900 to 1850 kilocycles, in case the intermediate frequency is 175 kilocycles. When the first tuned circuit is tuned as a whole to the signal frequency, the upper part of coil 4 and the condenser 5 form a resonant "rejector" 35 circuit between tap 6 and the ground. The rejector circuit contains a smaller inductance than that of the entire tuned circuit and is therefore always resonant to a frequency above the signal frequency. By proper location of the tap 6 on coil 4, the rejector circuit 40 can be made to tune over approximately the "image" frequency range. When the entire circuit 4, 5 is tuned over the broadcast band with the tap 6 at such a point as to give about 45% of the voltage existing across the entire 45 coil 4, the rejector circuit will tune over a range of from 750 to 2040 kilocycles. With a uniformly wound helical coil, 45% of the voltage would be obtained if the output included about 45% of the total number of 50 turns in the coil. It is to be noted that this gives approximately the "image" frequency range given above. The rejector circuit is, with a 45% tap, tuned exactly to the "image" 55 frequency of 1320 kilocycles when the signal frequency is 970 kilocycles.

The rejector circuit arranged with the proper location of tap 6 therefore greatly increases the attenuation of the "image" frequency as measured at tap 6. It can consequently be seen that the voltage-gain characteristic curve of the portion of the secondary 60 4 below the tap 6 will show zero voltage at the "image" frequency, whereas the natural resonance of the circuit may be such that a considerable voltage will be developed

at a frequency the same amount on the other side of the signal frequency, thus producing a non-symmetrical curve relative to the voltages of the tapped portion of the coil 4. It is desirable to couple circuit 4, 5 and circuit 9, 11 by an amount somewhere near the optimum value, which may be between 0.5% and 1%. This may be accomplished by making the capacity of the condenser 7 of the order of the minimum capacity of the circuit 75 9, 11 and making the capacity of the condenser 8 several times greater than the maximum of the capacity of the circuit 9, 11. There is no additional gain when this coupling is greater than optimum. Therefore, no loss of sensitivity results from coupling through condenser 7 to tap 6 instead of to the upper end of coil 4. There is also the definite advantage of the greater "image"- 80 frequency attenuation obtainable by taking the voltage from tap 6, as described above. 85

The second circuit 9, 11 is tuned to the signal frequency, and may or may not employ a tap connection similar to tap 6 on coil 4. 90 A similar tap 10 is shown in the diagram which would result in further increase in the attenuation of the "image" frequency. It is to be noted that the presence or absence of tap 10 does not affect the advantage to be 95 gained by use of tap 6. Tap 10 has the disadvantage of reducing the signal voltage output from circuit 9, 11 although the "image"-frequency reduction is more than the signal-frequency reduction. 100

It is convenient to refer to tap 6 as a node point relative to ground for the "image"-frequency current since there is approximately zero "image"-frequency voltage between this point and ground. Also, tap 6 and ground may be referred to collectively as node points at the "image" frequency. The use of condensers 7 and 8 to couple the two tuned circuits is not essential to the invention, since several useful and operative alternatives are known in the art. The essential feature is that the second tuned circuit is coupled to the first by means responsive to signal-frequency currents in the first tuned circuit and unresponsive to "image"-frequency currents 110 in the first tuned circuit. The preferred embodiment described herein includes in such means, the tap 6 for attenuating "image"-frequency currents and condensers 7 and 8 115 for conducting the signal-frequency currents. 120

What I claim is:

1. In a superheterodyne radio receiver, means for rejecting the "image" frequency, which comprise an input transformer, a tuned radio-frequency circuit including the secondary of said transformer, a second tuned radio-frequency circuit, and means connecting said tuned radio-frequency circuits, said last mentioned means including a connection to a portion of the first tuned circuit which 125 130 135

is at node potential relative to currents of the "image" frequency.

2. A radio-frequency tuning arrangement for a radio receiver, which comprises a circuit tuned to a current of the signal frequency, a second circuit tuned to the same frequency, a coupling circuit connecting said circuits, said coupling circuit being connected across a portion of the impedance of the first mentioned circuit, the terminals of which portion are at node potential relative to current of an undesired frequency and across a portion of the impedance of the second mentioned circuit.

3. In a superheterodyne receiver means for rejecting the "image" frequency which comprise a circuit resonant to the signal frequency, a second circuit resonant to the signal frequency, and means connecting said circuits connected at points in the first of said circuits which are at node potential relative to currents of the "image" frequency and connected across a part of the capacitive reactance of the second of said circuits, whereby the current of the image frequency is attenuated and the gain in amplification of the desired signal frequency current lost in said first mentioned circuit is compensated for by gain in amplification of said current in the second tuned circuit.

4. The combination of an electrical system responsive to a desired frequency and to an undesired frequency, which comprises a first circuit upon which are impressed signals of both of said frequencies, a second circuit connected to said system, both of said circuits being individually resonant to currents of the desired frequency, said first circuit including two points which are node points for currents of the undesired frequency, and a coupling circuit connected to said two points and coupled to said second circuit whereby signals having said undesired frequency are greatly attenuated.

5. The combination of an electrical system responsive to desired and undesired frequency current with a first circuit upon which are impressed currents of desired and undesired signal frequencies, a second circuit, said first and second circuits being individually resonant to currents of the desired signal, said first circuit having two points which are node points for currents of the undesired frequency, and a coupling circuit connected to said two points and coupled to said second circuit whereby signals having said undesired frequency are greatly attenuated, said coupling circuit providing substantially optimum coupling between said first and second circuits, whereby the attenuation of currents of said desired frequency is reduced to a minimum.

6. An electrical network adapted to select any desired frequency within a predetermined range and to simultaneously reject an undesired frequency which differs from said de-

sired frequency by a constant difference frequency, which comprises in combination an input circuit, an output circuit, and a coupling network, said input circuit having a variable tuning condenser and a fixed inductance, said inductance being divided in two parts by an intermediate tap, one of said parts being adapted to receive induced voltages from a signal-receiving device and having its terminals connected to said coupling network, said output circuit having a variable tuning condenser and a fixed inductance, said output circuit being coupled to said network and said circuits being tuned to resonance at said desired frequency.

7. An electrical network adapted to select any desired frequency within a predetermined range and simultaneously to reject an undesired frequency which differs from said desired frequency by a constant difference frequency, comprising in combination an input circuit, an output circuit, and a coupling network including in series a fixed capacity external to both of said circuits and a fixed capacity included in series with said output circuit, said input circuit having a variable tuning condenser and a fixed inductance divided in two parts by an intermediate tap, one of said two parts being adapted to receive induced voltages from a signal receiving device and having its terminals connected to said coupling network, said output circuit having a variable tuning condenser and a fixed inductance and said circuits being tuned to resonance at said desired frequency.

8. In a superheterodyne radio receiver means for rejecting the "image" frequency which comprises a circuit resonant to the signal frequency, a radio responsive device, and means connecting said radio responsive device to said circuit connected to points in said circuit which are at node potential relative to currents of the "image" frequency.

9. In a superheterodyne receiver means for rejecting the "image" frequency which comprises an input transformer, a tuned circuit including the secondary of said transformer, a radio responsive device and means connecting said radio responsive device and said tuned circuit, said means including a connection to the said tuned circuit which is at node potential relative to currents of the "image" frequency.

10. In a superheterodyne radio receiver means for rejecting the undesired "image" frequency currents which comprise an input transformer, an oscillatory circuit including the secondary of said transformer, a condenser for tuning said circuit, a radio responsive device, means for connecting said radio responsive device to said oscillatory circuit including connections to a portion of said oscillatory circuit, which connections are at node potential relative to current of the "image" frequency, said points being so selected that

said tuning means will vary the frequency to which said points are at node potential at the same time that it varies the tuning of the circuit to the desired signal, and the points will be at node potential relative to the "image" frequency at any desired point of the tuning range of said receiver.

11. In a superheterodyne radio receiver means for rejecting the undesired "image" frequency currents which comprise an input 10 transformer, an oscillatory circuit including the secondary of said transformer, a condenser for tuning said circuit, a second oscillatory circuit, a condenser for tuning said second 15 oscillatory circuit and means for coupling said oscillatory circuits including connections to a portion of the first mentioned oscillatory circuit, which connections are at node potential relative to currents of the "image" frequency, said points being so selected that the 20 tuning means of said circuit will vary the frequency to which said connections are at node potential at the same time that it varies the tuning of said circuit to the desired signal, and said points being so selected that the 25 connections will be at node potential relative to the image frequency at any desired point of the tuning range of said receiver.

12. In a superheterodyne radio receiver a 30 circuit adapted to suppress the "image" frequency which comprises a first tuned circuit, a variable condenser for tuning said circuit to cause it to respond to the frequency of the signal current, a second tuned circuit, a variable condenser adapted to tune the second 35 tuned circuit, to respond to the signal frequency, a circuit connecting said tuned circuits connected across a portion of the inductance of the first of said tuned circuits which are at node potential relative to 40 currents of the "image" frequency and coupled to the second tuned circuit, whereby currents of the image frequency will be attenuated and the currents of said signal frequency will be amplified in the second tuned circuit to compensate for the undesired attenuation of these signals in the first tuned circuit, a radio responsive device and a connection from said second tuned circuit to said 45 radio responsive device connected to a point in the inductance of the second tuned circuit which is at node potential relative to currents of the "image" frequency, whereby "image" frequency currents are further attenuated, 50 said tuning condensers being so disposed in each of said tuned circuits that they will simultaneously tune the frequency relative to which the selected points are at node potential and the frequency to which said circuits 55 are responsive.

In testimony whereof I affix my signature.
HAROLD A. WHEELER.
